SPRAY DRIED SOAP AND PROCESS OF
MAKING SAMECarleton Ellis, Montclair, N. J., assignor to The
Procter & Gamble Company, Cincinnati, Ohio,
a corporation of OhioNo Drawing. Application October 15, 1934,
Serial No. 748,364

3 Claims. (CL 87—16)

This invention relates to soap in a comminuted state obtained by spray drying soap having a substantial degree of hydration.

It has been proposed to spray dry soap solutions of a dilute character, or what would be generally called soap in the nigre form, and also to spray dry soap in the concentrated neat form, termed kettle soap. The dilute solution form of soap may range from stock containing 90% or more water, to possibly even as low as 60% of water. The kettle soap ordinarily contains about 30% of water, although at times it may be made with a somewhat higher proportion.

The spray drying of the dilute solutions of soap involves expenditure of inordinate amounts of fuel to eliminate the high proportion of water present. The product obtained from the employment of such dilute solution also tends to be a trifle too small in particle form, and too fragile to be of great commercial utility.

On the other hand the spray drying of neat, or kettle soap, with its component of approximately 30% of water may not permit so close an adjustment of drying conditions in ordinary commercial practice that a definite and controlled content of moisture appears in the resulting product.

Between the dilute solution of soap, or nigre type soap, and neat soap, or kettle type soap, there exists a zone commonly termed middle soap, which is a product of a peculiar condition of hydration forming stiff gummy masses, normally of far too high consistency to be usable in spray dry apparatus. See the article "Middle soap" by Ferguson & Richardson in Industrial & Engineering Chemistry, 1932, page 1329.

It should be understood in spray drying that nozzle apertures of very small diameters customarily are employed in order that resulting spray may be free from coarse particles. While, therefore, it is possible to spray dry dilute solutions of soap, as this is in a readily flowable condition, and likewise to spray-dry the more concentrated kettle soap, the extraordinary viscous gummy qualities of middle soap have heretofore precluded its use in the production of spray-dried detergents.

However, middle soap, (which is in what is termed the nematic state) contains water in combination with the soap molecules in the form of chemical water of hydration and the spray drying of a stock of this character permits the retention of the peculiarly-combined water characteristic, of middle soap to yield a spray dried

product having an adequate moisture content. This residual water seems to aid in conferring on the product an excellent degree of solubility when used as a detergent.

The spray drying operation as commonly practiced, with the use, for example, of the apparatus shown in the Lamont Patent 1,652,900 seemingly is not conducive to close and definite control of moisture content. A dilute solution of soap when sprayed thus, due to the size of the drop formation, or to absence of a definite condition of water of hydration, usually gives too dry a product, and also is inclined to be light, voluminous and dusty.

A product, which, when shaken out of a package for use as a detergent, forms a cloud of dust is objectionable and I seek in accordance with the present invention to obtain a particle formation of sufficient size, which is readily soluble and which avoids any objectionable formation of dust in use.

Although neat soap may be spray dried to a product having suitable particle formation, which is fairly uniform and generally free from dust, there is no opportunity in view of the small amount of water present in the neat, or kettle stock, to provide sufficient latitude in the spray drying step for retention of adequate moisture.

Middle soap, however, contains hydrated soap particles in a condition fully adequate for spray drying to obtain particles with a desired higher moisture content without the necessity of subsequent humidification, and the like.

As indicated, middle soap in its viscous state is of too high a degree of consistency to pass through spray nozzles, but it is possible, in accordance with the present invention to convert the middle soap into a more fluent, or liquid form, by incorporation of a degumming agent. In this way a stock may be secured for spraying purposes which is entirely suitable in consistency, and may be spray dried to yield a product containing if desired, 10% and upward of water—preferably a water content between the range of 10 and 20%. Despite this water content the material feels dry to the touch, and is free from any objectionable proportion of dust, while still being adequately soluble for household, or other purposes involving the use of soap.

A definite type of particle formation results from spray drying degummed middle soap; the usual appearance of the particle being that of a glassy, hollow ovule, or globule, the walls of which are not thin and fragile, such as result

from the spray drying of dilute solutions of soap. Furthermore, the relatively heavy wall structure is vesiculated due to the formation in such wall of tiny bubbles in the course of the spray drying

5 step.

It is also possible to introduce, as by air atomization under heavy pressure, and the like, a certain proportion of air into the material to increase the degree of vesiculation. However,

10 the main or essential cause of the formation of a particle of this character is, so far as I am advised, due to the evolution of the water of hydration contained in the middle soap; that is to say, water in the free state in the middle soap could

15 expand almost instantly when the sprayed particles enter the hot spray chamber giving the customary hollow spherical form characterizing spray dried products of various kinds other than those formed from soap. The chemically com-

20 bined water in the soap is not, however, liberated as quickly, and as the formed particle travels through the drying chamber becoming hotter as a result of such exposure, a temperature seems finally to be reached where chemical

25 water is given off creating the wall vesiculations and yielding what ordinarily appears to be a glassy particle of generally ovoid or globular form having walls carrying small secondary bubbles, or vesiculations.

30 It has been supposed that a glass-like particle would not have the same meritorious degree of solubility as the more opaque particle of spon- gious wall obtained by the spray drying of neat soap. But, by the employment of middle soap, 35 carrying soap material in a chemically hydrated state a quasi-glassy wall structure may be obtained so thoroughly vesiculated as to achieve extremely rapid solubility.

The advantages of a soap particle in the form 40 obtained by this invention are, among others, a high degree of particle rigidity and strength ascribed to origin from the presence of initial water corresponding to the middle phase; a good degree of solubility ascribed to a notable 45 condition of wall vesiculation; and a particle size adequate to confer freedom of flow of the dried material from its container and also a comparative freedom from dust.

Despite its vesiculations the wall strength is 50 adequate to give that degree of stability which provides a self sustaining particle, not readily fracturing in handling.

The middle soap stock, employed in accordance with the present invention, and containing 55 a degumming agent or component, may be prepared in different ways. A middle soap in a thick gummy condition may be produced by adding adequate water to neat soap, or any other concentrated soap material, and this gummy 60 stock may be beaten up by means of powerful mixers with the degumming agent, which preferably may be introduced substantially free from water in order not to upset in an objectionable way the degree of chemical hydration 65 desired in the stock employed in the present process.

Another way to obtain the middle soap is to evaporate water from dilute soap until the needed condition results. This, however, is a 70 more costly method, and is only mentioned by way of illustration.

On the other hand the degumming or fluxing agent in aqueous solution may be added to a soap stock which is in the neat range, the pro- 75 portion of water in such solution being sufficient

if no degumming agent is present to cause a decided thickening due to formation of normal gummy middle soap. Or part of the water may be added in the degumming solution and the remainder in any other suitable manner. The 5 batch is thoroughly agitated.

The product so made will be found no longer, extremely viscous and non-flowable, but will be adequately liquid for spray drying, especially when the stock is first heated and then pro- 10 pelled under pressure into the spray drying chamber. This method of operation is preferably employed in carrying out the present process.

Among the degumming agents are included 15 various alkaline salts such as; sodium carbonate, sodium bicarbonate, sodium acetate, sodium borate, or borax, tri-sodium phosphate, sodium silicate, or water glass, also non-alkaline salts such as; sodium chloride, sodium sulphate, and 20 the like. The employment of saponified rosin in minor proportion, likewise is not precluded. Most of the salts mentioned may be obtained sufficiently free from moisture so that their addition in requisite quantities to the middle 25 soap will not upset a desired condition of chemical hydration. Sodium silicate, however, is usually obtainable in the form of a solution which may carry perhaps 40% of silicate to 60% of water. The addition of sodium silicate solution 30 to the middle soap, or its incorporation with stock destined to be brought in the middle soap range should be such that due allowance is made for the added water, in order as stated, to avoid destruction of the chemically combined water of 35 hydration, conferring vesiculations within the wall structure, as previously pointed out.

Examples of compositions which may be used for purposes of illustration of this invention are the following:

Kettle (neat) soap was made in the usual way by saponifying fats with caustic soda. The fats used were 20 parts by weight of cocoanut oil to 80 parts of tallow. Water was added to give a total water content of about 50% yielding a 45 middle soap as a gummy mass.

Example 1.—To middle soap, as above, there was added 1% by weight of common salt (NaCl). In this example and following the proportions are by weight and the percentage of the de- 50 gumming agent is based on the total (not dry) weight of the middle soap. The salt was worked into the middle soap and on heating in a closed receptacle for a short time the gummy non- flowing properties of the middle soap dis- 55 appeared yielding a clear heavy bodied syrupy spray-stock material which flowed freely at 185° F.

Example 2.—Like Example 1, but with 3% of salt. At 185° F. flows more as a magma or 60 emulsion.

Example 3.—Like Example 1, but with 5% of salt. In a precipitated condition flowing as a magma at 185° F.

Example 4.—Sodium sulphate used, behaved 65 in a manner similar to sodium chloride.

Example 5.—Trisodium phosphate in the pro- 70 portion of 2% was used in place of sodium chloride. At 185° F. a free-flowing syrup re- sulted, not quite as clear as that obtained by Example 1.

Example 6.—A very liquid fluent syrup re- 75 sulted at 185° F. on incorporating in the middle soap 2% of trisodium phosphate and 2% of soda ash (anhydrous sodium carbonate).

Example 7.—Increasing the trisodium phosphate of Example 5 from 2% to 5% increased the consistency (at 185° F.) and reduced the flow.

Example 8.—10% of trisodium phosphate gave a still less fluent product of relatively slow flow.

Example 9.—A fair flow was obtained by incorporating the middle soap material with 2% of soda ash and 2% of sodium silicate solution (containing about 60% water).

Middle soap alone made as above when kept at 185° F. in a tight receptacle did not soften to a flowable condition.

In spraying the degummed middle soap care should be taken not to increase flowability to an extent such that very small fine particles make up the bulk of the finished spray-dried product and cause objectionable dust to arise when handling. By lowering the temperature of the degummed middle soap which may be too fluent at 185° F. to a lower point such as 170° F. or 140° F., and the like, a regulation of particle size is promoted. Thus there are several ways of regulating particle size.

- (a) Temperature control.
- (b) Soap pressure control.
- (c) Proportion of degumming agent.
- (d) In some cases adjustment of spray nozzles or change from a pressure type to air atomization is helpful.

Example 10.—Using the same middle soap stock introduce 1/2% up to 1 1/2% of caustic soda.

When the degumming agent is added in such proportion that the composition (maintained by heat in a flowable condition) tends ultimately to show considerable precipitation, the composition preferably is spray-dried prior to the beginning of precipitation. Since the latter change takes place slowly there is afforded in most cases sufficient time to spray-dry the dispersion. The invention also contemplates the spray-drying of flowable dispersions which if allowed to stand in their initial state in a heated atmosphere would coagulate or precipitate to form slurries.

Preferably, however, I use a relatively low proportion of the degumming agent ranging in most cases from less than 1% to 2 or 3%.

When rosin is present in considerable proportion, the relative quantity of the degumming agent may be decreased, if desired, in any suitable proportion but preferably in the ratio of reduction (when the degumming agent is present in an amount above three percent and upwards to ten percent or higher) of about one percent for each five percent of rosin soap present.

It should, however, be borne in mind that rosin impairs the color of the dried soap and, if present in high proportion, tends to induce an undesirable degree of hydroscopicity. Rosin, therefore, should be used only in the cheaper grades of the vesiculated soap product.

Example 11.—Instead of using 10% of trisodium phosphate as in Example 8, use 9% with 5% of rosin soap (sodium abietate etc.) adding the mixture in aqueous solution to neat soap, the proportion of water in the solution being sufficient on thorough incorporation with the hot neat soap to institute in the latter what would normally be unworkable middle soap, but which, in the presence of the rosin saponified material, the phosphate compound becomes fluent and sprayable.

Example 12.—A neat soap was made from cocoanut oil 50 parts, tallow 10 parts and hydrogenated fish oil 40 parts, by saponifying in the

usual way with caustic soda. This was incorporated with soda ash 4% and water to make a total water content of 44%. The material was spray-dried by forcing from the supply at 20 lbs. pressure and using an atomizing nozzle supplied with steam at 5 lbs. pressure. The heated air for drying entered the drying chamber or tower at a temperature of 420° F. Good sized particles large enough to be visible to the naked eye resulted.

Example 13.—A soap product of a 20-80 cocoanut oil-tallow composition was made up to contain 2% common salt and a water content of 44.6%. This was also spray-dried at the same air temperature (420° F.) and at the same soap pressure. Glassy but slightly opaque particles of the desired good size were obtained, containing 14.6% of total moisture.

In carrying out the spray drying I prefer, as stated, to heat the degummed middle soap and place it under pressure—the temperature of the soap and pressure being adjusted to provide a product which will flow freely from the spray nozzle without formations of slugs or strings of soap yielding objectionably large particles, or ones that would be imperfectly dried. While not limiting myself to any particular degree of pressure or temperature I may spray under a pressure of say, between 50 and 300 pounds with the degummed middle soap at a temperature of about 150° to 200° F., or higher, or lower.

The spray drying chamber is supplied with an abundance of preheated air at the temperature appropriate to form the glassy particle of vesiculated wall structure. The air temperature may range, preferably, between 350 and 500° F., but higher or lower temperatures may be employed in some cases. Preferably I seek to have so large a volume of heated air in proportion to the amount of the middle soap supplied that the temperature of the exit gases is at, or near, the boiling point of water; this being with the employment of initial air preheated to within the range of the temperature specified. It should be understood, however, that if lower temperatures are employed chambers of greater dimensions are needed in order to secure a sufficiently prolonged exposure of the spray material to drying action.

The heated air may be brought into contact with the spray of the degummed middle soap in any suitable manner, such as with any one of the well known spray drying systems using either concurrent or countercurrent flow of the drying air, and the like.

Although the term middle soap is recognized to apply to that phase of soap in which an extremely gummy state obtains, I consider for the purposes of this invention that the degummed product also is middle soap, and have used the terms interchangeably in the foregoing.

In some operations of the drying art it has been customary to spray-dry neat soap under temperature conditions which produce an inflated particle, but the present invention does not ordinarily contemplate puffing or inflating the particle to any substantial extent; although this may be done, if desired, by the regulation and control of temperatures and other conditions as the art prescribes for making the inflated particle from kettle soap. I desire especially to obtain a powdered soap in fairly compact form, and the distention of the soap particle by such inflation step adds bulk without a

corresponding increase in amount of detergent present. I seek, therefore, to produce a bulk product which as a whole is denser, and, therefore, prefer that the temperature control, and the like, be of such a character that a non-puffed, or only slightly puffed particle results.

Thus, I may obtain a product composed substantially of hollow glass-like wall-vesiculated and substantially non-puffed particles of middle soap range carrying a degumming agent. Further if the degumming agent is of the electrolyte type I may, in some cases, increase the content thereof to a point where actual precipitation of the chemically-hydrated middle soap results, thus forming a slurry or magma.

In this case, however, care should be taken not to introduce a quantity of electrolyte substantially in excess of that which the soap wall can carry without undue crystallization of the electrolyte material causing crystals thereof to separate from the soap particles themselves. From this, however, it should not be inferred that there may not be some indications of crystallization visible, but to no such extent as that which would appear in the ordinary soap powder, which commonly contains about 20%

of soap, the remainder being largely hydrated soda ash in crystallized form.

In this case I merely seek when desired to provide a proportion of electrolyte only slightly in excess of that which constitutes wall-saturation.

What I claim is:

1. The process for making comminuted soap which comprises preparing a soap composition consisting of middle soap together with a degumming agent in sufficient proportion to reduce the viscosity to a sprayable condition but not sufficient to cause a separation of crystalline material from the soap, spraying the same into a chamber heated by a current of heated 1 gas, and collecting the dried soap as finely divided material composed largely of hollow glass-like, wall-vesiculated, substantially non-puffed particles.

2. Process according to claim 1 wherein a middle-soap degumming agent is employed in proportion slightly in excess of wall saturation in the final product.

3. Process according to claim 1 wherein the proportion of degumming agent does not exceed 3 per cent of the material as sprayed.

CARLETON ELLIS.
